UNITED STATES PATENT OFFICE.

JOSEPH H. CHAMP, OF CLEVELAND, OHIO.

FEEDING MECHANISM FOR BOTTLING-MACHINES.

1,234,729.

Specification of Letters Patent. Patented July 31, 1917.

Application filed January 21, 1913. Serial No. 743,396.

To all whom it may concern:

Be it known that I, JOSEPH H. CHAMP, a citizen of the United States, and a resident of Cleveland, county of Cuyahoga, and State of Ohio, have invented a new and useful Improvement in Feeding Mechanism for Bottling-Machines, of which the following is a specification, the principle of the invention being herein explained and the best mode in which I have contemplated applying that principle, so as to distinguish it from other inventions.

The present improvements more particularly relate to the handling of bottles in connection with bottle filling machines of the continuous, rotating type, such as illustrated in my Patent No. 956,285, dated April 20, 1910. In other words, it is designed by these improvements not only to automatically feed the empty bottles onto the successive holders of the filling machine, but also to similarly remove the bottles therefrom. In certain fields of use the bottles, when discharged from the filling machine are desirably carried before operators who manually cork the same, using rubber stoppers in place of "crown" seals, which latter are put onto the bottles by automatic machines. The present invention, accordingly, further comprehends an arrangement or layout of conveying mechanism which provides, not merely for the convenient bringing up of the empty bottles and their feeding onto the machine, but also for the removal and convenient disposition of the filled bottles for the corking operation, where stoppers are used requiring manipulation on the part of operators stationed for the purpose.

To the accomplishment of the foregoing and related ends, the invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

50 In said annexed drawings:

Figure 1 is a plan view of my improved bottle handling mechanism in proper relation to that portion of the filling machine wherewith it coöperates; Fig. 2 is a side elevation of such bottle handling mechanism; Fig. 3 is a plan view on an enlarged

scale of certain operative parts of the mechanism directly associated with the feeding of the bottles onto the bottle holders of the filling machine and the removal of such bottles therefrom; Fig. 4 is a transverse section of the foregoing parts taken on the line 4—4 Fig. 3; Fig. 5 is a transverse section of another detail of the mechanism taken on the plane indicated by the lines 5—5 in Fig. 1; Fig. 6 is a section of another detail taken on the line 6—6, Fig. 1; Figs. 7 and 8 illustrate a modification in the construction of the supports for the pulleys around which the conveyer belts run; Fig. 70 9 illustrates a detail of one of the bottle guides; and Fig. 10 shows a preferred arrangement of driving means for driving the aforesaid conveyer belts.

As has been indicated, the mechanism 75 illustrated in the drawings just described is designed primarily for use where the bottles, after being discharged from the filling machine, require to be manually handled incidentally to corking or other operation 80 performed thereon. It will be understood, however, that the several features of improvement embodied herein are not necessarily limited to use in this precise combination, and that the feeding and discharging 85 mechanisms for example, may be employed in conjunction with automatic sealing machines, which would not make necessary the provision of such an extensive conveyer table with the adjuncts here shown. 90

The conveyer table 1 as shown in Figs. 1 and 2 is of considerably greater extent longitudinally than transversely, said table being furthermore jointed or hinged at 2, so as to permit the portion 3 thereof projecting to the right beyond the filling machine (as shown in said figures), to be folded back above the other portion out of the way, when the mechanism is not in actual use. The portion of the table 1 adjacent to the filling machine, of which only two of the corner supports 4 of the frame, together with a few of the bottle holders 5 are shown, is cut out on a curve corresponding with the circular path of travel of said 100 holders and is disposed in the same plane which said holders occupy when in position for receiving the empty bottles 6. Said holders, it will be understood, are lowered again to this same plane when the bottles are to be 105 discharged.

Brackets 7 extending from the corner

posts 4 of the filling machine, together with supplemental posts or standards 8 serve to support the conveyer table, such supporting members permitting of the vertical adjustment of the table to bring the same in the desired plane as just explained.

Running the entire length of the table are two conveyer belts 9 and 10 traveling in opposite directions as indicated by arrows 10 in Figs. 1 and 2, the upper laps of said belts being slidably supported upon the smooth upper surface of the table and passing around rollers or pulleys 11, 11, and 12, 12, at the respective ends of the tables, while 15 idler pulleys 13, 13 carried by swinging arms 14, 14 rest upon the lower laps of the belts and maintain said belts under proper tension. The swinging arms 14, 14 which carry said idler pulleys are pivotally attached to the table on approximately the same axis 2 about which the portion 3 is hinged, so that the latter may be turned up into the position indicated in dotted outline in Fig. 2, and the belts readily accommodate themselves to the change in position without becoming either loose or entangled with the other parts of the mechanism.

For driving belts 9 and 10 a chain drive is preferably employed, such drive consisting of a single chain 15 passing around a double sprocket 16 of the driving shaft 17 and thence around two separate sprockets 18, 18 attached to the respective rollers or pulleys 11, 11 around which pass said two belts (see Figs. 1, 2 and 9). The arrangement of the chain, as will clearly appear from inspection of the last-named of these three figures, is such that, with the driving sprocket 16 turning continuously in one direction, the two driven sprockets 18, 18 with their attached rollers 11, 11, will be rotated in opposite directions.

Supported above the upper surface of the table, and of the conveyer belts traveling thereon in opposite directions, as just described, are guides 19 disposed along each side of the table and between the inner edges of the belts, which are spaced some distance from each other. In fact this central guide 45 is desirably left of such width that it may serve as a shelf on which to place bottles that are to be discarded, or are improperly filled, or for any other reason require to be removed from the general lot. At each end 50 of the table there is, moreover, a curved guide 20 similarly supported above the table top, which guide 20 joins the outer guides and is suitably spaced from the end of the inner guide to leave a continuous, closed 55 path for the bottles to travel down with the one conveyer belt 9 and back on the other conveyer 10.

To facilitate the transfer of the bottles at the respective ends of the table from the one belt to the other, a thin flat disk 21 is ro-

tatably supported with its under surface resting on the two belts and with its axis of rotation midway between them and just at the end of the central guide 19. The weight of this disk, which may be augmented by attaching a weight 22 to the bolt or spindle 23 which pivotally secures the same to the table, as shown in Fig. 5, produces sufficient frictional contact between said disk and the two belts so that the latter will rotate each disk in the direction indicated by the arrows in Fig. 1. The disks, however, are sufficiently thin so that a bottle traveling on the one belt will slide onto the disk and be carried around by it and discharged onto the other belt without difficulty.

By reason of the recess in the inner edge of the conveyer table 1, the corresponding edge of the conveyer belt 10 on that side of the table, is brought into substantially tangent relation to the circular path of travel of the bottle holders 5 of the filling machine, at a point approximately midway between the two posts 4 of the filling machine frame. The inner guide 19 on the table is interrupted for some distance on either side of this point and special mechanism provided there, for transferring the empty bottles on to the successive holders of the filling machine, as they are brought up to this point by the inner belt, and for removing the bottles from said holders onto the same belt, as they are brought around again nearly to this point, to be carried toward the right hand end of the table as viewed in Figs. 1 and 2.

Noting first the device for feeding the empty bottles onto the holders of the filling machine, the principal element comprised in said device is a pivotal gate member 24 oscillatory in a substantially horizontal plane and of the conformation appearing in Figs. 1 and 3 as there shown. The forward end of this member comprises a concave portion 25 adapted to receive a bottle for the purpose of transferring the same on to the adjacent holder when the member is swung inwardly, and a convex portion 26 which, when interposed in front of the line of bottles on the conveyer belt, serves as a stop to prevent the further progress of said bottles. A weight 27 adjustable on a rocker-arm 28 supported from a bracket 29 beneath the table, is connected by means of a lever 30 and connecting rod 31 with the opposite end of this gate member, so as to normally retain the same in the position illustrated in Fig. 1, where the member acts as a stop. In such position, an arm 32 integral with the member and carrying a roller 33 to reduce the friction, extends inwardly toward the filling machine into a position where it will be engaged by the bottle holders 5, or some corresponding part of the machine. The member is thereby locked into the position illustrated in Fig. 3, where the stop portion 115 120 125 130

26 of the member is carried out of line with the bottles resting on the conveyer belt 10, and the concave portion 25 of said member disposed to receive the foremost bottle in 5 said line. Immediately, however, that the particular bottle holder which thus actuates the member has passed beyond the point shown in Fig. 3, the roller-bearing arm 32 is released, and the weight 27 swings the 10 gate 24 back into the position of Fig. 1. This movement carries, or transfers the particular bottle engaged by the recessed portion 25 of the member off the belt 10 and onto the adjacent bottle holder 5 which will 15 be positioned to receive the same by the time this movement is consummated.

The point of transfer is not exactly that at which the line of travel of the bottles on the belt is tangent to the circular path of 20 travel of the bottle holders, but to the left of such point, as will be obvious from a reference to Fig. 1. Accordingly, the holder is in a sense moving away from the bottle when the latter is thus being transferred, 25 and this is purposely so designed, since I have found that there is much less tendency for the bottle to break between the moving parts when the latter are thus relatively disposed, than where the transfer takes place 30 at a point substantially tangent to the path of travel of the holders.

The section 34 of the guide 19 adjacent the transfer point of the empty bottles onto the holders of the filling machine, is pivotally secured to the table at the point 35, so as to be capable of a limited amount of oscillation in a horizontal plane. The free end of such swinging guide section is, moreover, recurved so as to assist in forcing the 40 bottles back into the holders after they have been transferred by the swinging gate member. Said guide section is backed by a spring 36 so that a certain amount of resilience is assured its action.

45 By suitably adjusting the weight 27 along the rocker arm 28, just the proper amount of force to effect the transfer of the particular size of bottles being dealt with can be secured, and accommodation is furthermore 50 made for handling different sizes of bottles by attaching to the resiliently supported pivotal section 34 of the guide, a plate 37 (see Fig. 9), which serves to constrict the width of the passage along which the empty bottles 55 are conveyed, sufficiently to prevent such bottles being shoved out of line when the gate member 24 is positioned to serve as a stop.

As the filled bottles are brought around 60 on the holders 5 of the filling machine to a point adjacent to the feeding point, as shown in Fig. 1, they are engaged by an arm or finger 38 that is pivotally mounted on a support 39 beside the gate member, such 65 finger being inclined at the proper angle to

the direction of movement of the holders to force said bottles from the latter with a wedging or cam action, the flanges on the holders being inclined at the proper angle to coöperate with this finger in producing 70 the desired result.

As the bottles are thus shoved off the successive holders they are received onto the same belt 10 which brings the empty bottles up to the feeding station, said belt extending for a sufficient distance beyond this point to afford an opportunity for one or more operators, stationed beside the table, to attend to the corking. Such bottles will be removed as fast as corked into trays, or 75 crates, disposed by the side of the operator, or if for any reason a bottle requires to be set aside, it may be placed on the shelf-like central guide member 19. Should the rate of operation be such that a single operator 80 can not take care of the corking, one may be stationed on either side of the table extension 3, since the bottles will be transferred from the rear belt to the front belt by the rotating disk at the end of said table, 85 just as the empty bottles are carried across the other end of the table.

The finger 38, which thus serves to remove the bottles from the holders, is normally held in the position where it thus operates 90 by a compression spring 40 surrounding a rod 41 eccentrically connected with said finger, as clearly shown in Fig. 3. Should, however, the bottle stick on the holder, or, what is more apt to happen, the holder fail 95 to lower properly, so that the finger strikes an unyielding structure, it will be swung out of the path of the holder into the position indicated by dotted lines in said Fig. 3 and there retained by the action of the 100 spring which now lies to the other side of the pivotal axis of the finger. In this inoperative position of the latter it engages the inwardly extending roller-bearing arm 105 32 of the gate member 24 and holds the 110 same in the position where the recessed portion 25 of said member is disposed to receive the bottles, and the roller on the arm thus held out of the path of travel of the 115 holders 5. The spring is designed to be 120 strong enough to overcome the tendency of the weight 27 to force the gate member into its other position, so that said gate member is effectually locked and the feeding operation thus automatically stopped until the operator restores the finger to its normal 125 operation, first, of course, correcting the cause of the disturbance.

The foregoing described means provide a simple and very effective mechanism for 130 handling bottles in connection with a bottle filling machine of the class in mind, and it has been found by actual experiment that the difficulties heretofore encountered with automatic bottle handling machines for use 130

in such connection, such as the upsetting and breaking of bottles, is effectively done away with. It is, of course, immaterial what be the extent of the table, and where an automatic corking or sealing machine is employed it will suffice if the conveyer belt, that carries the filled bottles away from the machine, simply carries such bottles to such sealing machine, without a special extension for the manual handling of the bottles being provided, as in the present case.

In the modification shown in Figs. 7 and 8, the rollers 12 are carried by brackets 45 that are adjustably attached to the table by set-bolts 46. The tension of the belts 9 and 10, may, by this means, be still further varied.

In referring herein to operation of the gate-member 24 by engagement of successive holders 5 with the roller-bearing arm 32 of said member, it will be understood that said holders merely typify any corresponding, spaced elements on the rotatable, or moving, portion of the filling machine, which are adapted one after the other to thus actuate the member. The holders, specifically, are desirably utilized in the particular patented machine previously referred to because in such machine they have a vertical reciprocatory movement, and unless lowered into the proper plane (*i. e.*, that of the table 1), the gate member 24 should of course not be actuated. The same remark applies to operation of the finger 38, which normally lies above the plane of the holders when in proper lowered position for the discharge of the filled bottles, but which will be engaged by said holders, or their supports, if the latter are not thus positioned.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. The combination with a machine of the character described having a series of conjointly movable holders for bottles or the like; of a conveyer passing adjacent to the path of movement of said holders; an oscillatory member having one portion adapted to receive and transfer a bottle from said conveyer to a holder and another portion adapted to stop the movement of the bottles by said conveyer; and means normally retaining such stop-portion of said member in operative position.

2. The combination with a machine of the character described having a series of conjointly movable holders for bottles or the like; of a conveyer passing adjacent to the path of movement of said holder; an oscillatory member having one portion adapted

to receive and transfer a bottle from said conveyer to a holder and another portion adapted to stop the movement of the bottles by said conveyer; and gravity-actuated means normally retaining such stop-portion of said member in operative position.

3. The combination with a machine of the character described having a series of conjointly movable holders for bottles or the like; of a conveyer passing adjacent to the path of movement of said holder; an oscillatory member having one portion adapted to receive and transfer a bottle from said conveyer to a holder and another portion adapted to stop the movement of the bottles by said conveyer; means tending to move said member to place such stop-portion thereof in operative position; and means adapted to move said member into position to receive a bottle, said first-named means being thereupon adapted positively to transfer the bottle, thus received, onto an adjacent holder.

4. The combination with a machine of the character described having a series of conjointly movable holders for bottles or the like; of a conveyer passing adjacent to the path of movement of said holder; an oscillatory member having one portion adapted to receive and transfer a bottle from said conveyer to a holder and another portion adapted to stop the movement of the bottles by said conveyer; gravity-actuated means tending to move said member to place such stop-portion thereof in operative position; and means adapted to move said member into position to receive a bottle, said first-named means being thereupon adapted positively to transfer the bottle, thus received, onto an adjacent holder.

5. The combination with a machine of the character described having a series of conjointly movable holders for bottles or the like; of a conveyer passing adjacent to the path of movement of said holder; an oscillatory member having one portion adapted to receive and transfer a bottle from said conveyer to a holder and another portion adapted to stop the movement of the bottles by said conveyer; gravity-actuated means tending to move said member to place such stop-portion thereof in operative position; and means operable by said holders to move said member in position to receive a bottle, said first-named means being thereupon adapted positively to transfer the bottle, thus received, onto an adjacent holder.

6. The combination with a machine of the character described having a series of conjointly movable holders for bottles or the like; of a conveyer passing adjacent to the path of movement of said holder; a pivotal finger adapted in one position to transfer bottles from successive holders onto said conveyer and in another position to lie clear

of such bottles; and a spring connected with said finger eccentrically of its axis and tending to retain the same in whichever position it is placed.

- 5 7. The combination with a machine of the character described having a series of conjointly movable holders for bottles or the like; of a conveyer passing adjacent to the path of movement of said holder; an oscillatory member having one portion adapted to receive and transfer a bottle from said conveyer to a holder and another portion

adapted to stop the movement of the bottles by said conveyer; a lever connected with said member to oscillate the same; and a 15 weight adjustable on said lever and tending to retain said member with its stop-portion in operative position.

Signed by me, this 18th day of January, 1913.
